UNITED STATES PATENT OFFICE.

JOHN C. BROOKS, OF PATERSON, NEW JERSEY, ASSIGNOR TO DRAPER CORPORATION, OF HOPEDALE, MASSACHUSETTS, A CORPORATION OF MAINE.

FEELER MECHANISM FOR LOOMS.

Application filed May 18, 1925. Serial No. 31,000.

To all whom it may concern:

Be it known that I, JOHN C. BROOKS, a citizen of the United States, residing in Paterson, in the county of Passaic and State of New Jersey, have invented an Improvement in Feeler Mechanisms for Looms, of which the following description, in connection with the accompanying drawings, is a specification, like characters on the drawings representing like parts.

This invention relates to feeler mechanisms for looms whereby the operative condition of the loom is changed from time to time, and more particularly to feeler mechanisms of the magnetic type.

Heretofore, magnetic feeler mechanisms have been devised, but their operation in practice has not been satisfactory owing to conditions attending their operation, and one of the purposes of the present invention is to provide a feeler mechanism of the magnetic type which shall be simple in construction and effective and satisfactory in operation.

In accordance with the present invention, the feeler itself is mounted to be drawn rearwardly upon detection of substantial exhaustion of the filling, to thereby position parts relative to each other for effecting a change in the loom operation, such as replenishment of filling, on the following detecting beat of the lay. In carrying this feature of the invention into effect, the feeler itself is mounted for movement towards and from the front of the loom in bearings which permit the feeler a bodily movement transversely to its rearward movement when it is drawn rearwardly on detection of substantial exhaustion of filling, to thereby relatively position the feeler and a shouldered member for effecting replenishment of filling when the feeler is again moved frontwardly on the next detecting beat of the lay.

The feeler mechanism of the present invention is applicable to either the replenishing or opposite side of the lay, and the parts are so arranged that on the forward movement of the feeler when engaged with the shouldered member, it will itself be withdrawn frontwardly out of the shuttle box, to thereby permit a change of filling carriers in the shuttle should the feeler be employed at the replenishing side of the loom.

The invention and novel features and new combination of parts will best be made clear from the following description and the accompanying drawings of one good form thereof.

In the drawings:

Fig. 1 is a perspective view of the main parts of a loom at the shipper side, containing the present invention, the parts being shown in their normal position;

Fig. 2 is an enlarged sectional side elevation of the feeler mechanism of the present invention, showing the feeler as having been drawn rearwardly on detection of substantial exhaustion of filling;

Fig. 3 is a similar sectional side elevation showing the relation of parts initially positioned for effecting replenishment of filling;

Fig. 4 is an enlarged detail showing a filling carrier or bobbin which may be advantageously employed in connection with the feeler mechanism of the present invention.

The feeler mechanism is shown associated with loom replenishing devices, but the latter are not illustrated because the details thereof form no part of the present invention and are now well understood in the art.

The loom frame 1 has mounted on the breast beam 2 thereof the bearings 3, one at each side of the loom, in which is supported the transverse or rock shaft 4 from which rises the arm 5 connected at 6 to a rearwardly extending arm or actuator 7. The rear portion of the actuator 7 is provided with a finger 8 adapted to be engaged at times by an operating member 9 which may be the cam follower or a part associated therewith.

Underlying the actuator 7 is the arm 10 pivotally mounted on the loom frame at 11 and having the usual cam portion 12 above which extends an arm 13 pivotally supported at 14 and normally pressed rearward by a spring 15. This train of devices between the feeler mechanism and the transverse or rock shaft 4 is, or may be, of usual type, or be varied, if desired, the essential being that on detection of substantial exhaustion of filling and call for replenishment, the actuator 7 shall be placed in operative relation with the operating member 9.

The lay 16 may be of usual construction and has the shuttle box 17, the front wall of

which has an opening 18 which registers with a similar opening 19 in the front wall of the shuttle 20 when the latter is in the shuttle box. These parts may be of usual construction.

Adjustably mounted on the shipper stand 21 is the feeler support or stand which, as shown, comprises a base 22, Fig. 2, having slots through which pass the bolts 23 for securing the shipper stand in place.

The feeler stand has a front and a rear bearing for the feeler, and as shown the front bearing comprises an opening 24 in the upwardly extending member 25 of the feeler stand, the lower wall of the bearing 24 being chamfered or cut away from its center towards its edge portions, as indicated at 26. The rear bearing for the feeler is formed in the upstanding member 27 and is also chamfered on its lower wall by a downward inclination thereof, as indicated at 28, the construction being such that the feeler 29 may not only have a movement towards and from the front of the loom in such bearings, but also a movement transversely to its frontward and rearward movement, or, as in the present instance, in a downward direction, as will presently appear.

30 The feeler 29 at its front portion adjacent the front bearing is cut away or recessed at 30, and through a slot or opening 31 therein extends the arm 32 of a lever pivoted at 33 and having the frontwardly extending flat portion 34, on the top of which is adapted to bear the spring 35 which, in the present instance, is shown as a leaf spring, having its front end portion 36 upturned, the construction being such that the spring 35 acts through the pivoted lever to normally hold the feeler in its position of detection of filling, but with permissive movement both rearwardly and frontwardly, as will further appear.

45 The tip end portion 37 of the feeler may be formed either as a permanent magnet or it may be an electric magnet by the use of the electric wires 38, but the details of such magnet or electric magnet may be varied widely within the true scope of the invention, the essential being in this respect that the tip portion of the feeler will be magnetized to cooperate with a metal band 39, which may be secured to the filling carrier or bobbin 40, otherwise of usual type, as indicated in Fig. 4, the construction being such that when the feeler detects substantial exhaustion of filling in the shuttle on a detecting beat, it will be drawn rearwardly, and to limit such rearward movement, a stop 41 is adjustably secured to the feeler frontward of the rear bearing 27.

When the feeler is drawn rearwardly as the lay goes back on a detecting beat and upon substantial exhaustion of filling, which

uncovers the band 39, it will drop in the chamfered bearings 26, 28, as indicated in Fig. 2, and advantage is taken of this dropping or transverse movement of the feeler on its rearward drawing movement to operatively position the parts for effecting replenishment of filling on the following detecting beat.

70 The feeler 29 has adjustably secured thereto a projection or tooth 42 which may be clamped in adjusting position by a bolt 43, and below the feeler is mounted a shouldered member or slide 44 having a shoulder 45 adapted to be engaged by the projection 42 when, as the feeler is drawn rearwardly, it is lowered or moved transversely in its chamfered bearings.

75 The shouldered member or slide 44 is mounted in the front and rear upstanding members 25 and 27 and has a collar 46 which may appropriately limit its rearward movement.

80 Pivotedly mounted in the feeler stand at 47 is the dog positioner, shown formed as a lever, one arm 48 of which normally rests against the front end portion 49 of the shouldered member or slide 44, and the other arm 50 of which is connected at 51 to a link 52, the lower end portion of which has a slot 53 which engages a pin 54 on a dog 55 which is itself connected at 56 to the downwardly extending arm 57 of the transmitter 13, the construction being such that should the dog be moved frontwardly it will 90 act through the transmitter to operatively relate the parts for effecting replenishment of filling.

95 In accordance with the present invention, the lay 16 has mounted thereon a bunter 58 which is adapted to engage the dog 55 when the latter is operatively positioned by the dog positioner. Adjacent the bunter 58 is a lug 59 which, when the dog positioner has been initially moved by the shouldered member or slide 44, engages the inclined end portion 60 of the dog positioner which has been initially raised, as indicated in Fig. 3, and thus insures that the dog itself shall be moved to operative position with relation to the bunter 58. By this construction of the lug 59 and inclined end 60 of the dog positioner, the stress of moving the dog into the path of the bunter is removed from the shouldered member or slide 44 after the initial positioning of the parts.

100 The front end portion of the feeler is provided with a downturned toe or foot 61, and between it and the shouldered member or slide 44 extends the enlarged end portion of the arm 48 of the dog positioner, with the result that when the dog positioner assumes its full transferring position, the feeler itself will be moved frontwardly or withdrawn from the shuttle box.

105 110 115 120 125 130 From the construction hereinbefore de-

scribed as one good practical form of the present invention, it will appear that during normal weaving operations with a working supply of filling in the shuttle, the feeler 5 will be given a frontward movement on its detecting beat and thereby swing the lever 32 frontwardly, and as the lay goes back the spring 35 acting upon the flat portion 34 of the lever 32 will return the feeler to its initial position. When, however, the filling had become substantially exhausted and the metal band 39 on the filling carrier or bobbin is exposed, the magnet or magnetic tip 37 of the feeler will cause the feeler to be 10 withdrawn rearwardly as the lay goes back, thereby bringing the recessed portion 30 of the feeler rearward to permit a drop of the feeler and cause the projection 42 to engage rearward of the shoulder 45 extending from the slide 44. On the next detecting beat, the feeler will again engage the filling carrier or bobbin in the shuttle and be moved frontwardly thereby. Such frontward movement of the feeler on the second detecting 15 beat effects frontward movement of the shouldered member or slide 44, thereby actuating the dog positioner and operatively relating the parts to effect replenishment of filling.

30 What is claimed is:

1. In a feeler mechanism for looms, the combination of a feeler having a magnetic tip that causes the feeler to be moved rearwardly on detection of substantial exhaustion of filling in the shuttle and by such movement to be lowered to initiate replenishment of filling as the feeler is moved frontwardly on the next detecting beat, and means actuated by such frontward movement of the feeler for effecting replenishment of filling.

2. In a feeler mechanism for looms, the combination of a feeler having a magnetic tip by which it is moved rearwardly on detection of substantial exhaustion of the filling, means operatively positioned by such rearward movement of the feeler to effect replenishment of filling by frontward movement of the feeler on the next detecting beat and means for normally holding the feeler in feeling position.

3. In a feeler mechanism for looms, the combination of a feeler having a magnetic tip by which it is moved rearwardly on detection of substantial exhaustion of the filling, a slide adjacent the feeler and having a shoulder, a projection extending from the feeler adapted to engage said shoulder when the feeler is moved rearwardly as described and by which the slide is moved frontwardly on the following detecting beat, and means positioned by the slide as it is moved frontwardly to effect a change in the loom operation.

4. In a feeler mechanism for looms, the

combination of a feeler having a magnetic tip by which it is drawn rearwardly on detection of substantial exhaustion of filling, a slide arranged parallel to the feeler and having a shoulder, a projection on the feeler adapted to engage rearwardly of the shoulder when the feeler is drawn rearwardly, and means controlled by the slide as it is moved frontwardly by the feeler on the next detecting beat to effect replenishment of filling.

5. In a feeler mechanism for looms, the combination of a feeler having a magnetic tip by which it is drawn rearwardly on detection of substantial exhaustion of filling, a slide arranged parallel to the feeler and having a shoulder, a projection on the feeler adapted to engage rearwardly of the shoulder when the feeler is drawn rearwardly, and means controlled by the slide as it is moved frontwardly by the feeler on the next detecting beat to effect replenishment of filling and withdraw the feeler frontwardly from the shuttle box.

6. In a feeler mechanism for looms, the combination of a feeler having a magnetic tip by which it is drawn rearwardly on detection of substantial exhaustion of filling, a stop for limiting the rearward movement of the feeler as the lay goes back, a slide arranged parallel to the feeler and having a shoulder, a projection on the feeler adapted to engage rearwardly of the shoulder when the feeler is drawn rearwardly and means controlled by the slide as it is moved frontwardly by the feeler on the next detecting beat to effect replenishment of filling.

7. In a feeler mechanism for looms, the combination of a feeler having a magnetic tip by which it is drawn rearwardly on detection of substantial exhaustion of filling, a slide arranged parallel to the feeler and having a shoulder, bearings in which the feeler is movable towards the slide as it is drawn rearwardly, a projection on the feeler adapted to engage rearwardly of the shoulder when the feeler is drawn rearwardly, and means controlled by the slide as it is moved frontwardly by the feeler on the next detecting beat to effect replenishment of filling.

8. In a feeler mechanism for looms, the combination of a magnetic feeler adapted to be drawn rearwardly on detection of substantial exhaustion of filling, a dog adapted to be positioned for movement by the lay, a dog positioner member, a shouldered member adapted to act upon the positioning member, bearings in which the feeler is movable towards the shouldered member to engage therewith when the feeler is drawn rearwardly, and means to move the shouldered member on the next movement of the feeler frontwardly to effect a change in the loom operation.

9. In a feeler mechanism for looms, the combination of a magnetic feeler adapted to be drawn rearwardly on detection of substantial exhaustion of filling, a dog adapted to be positioned for movement by the lay, a dog positioner member, a shouldered member adapted to act upon the positioning member, bearings in which the feeler is movable towards the shouldered member to engage therewith when the feeler is drawn rearwardly, means to move the shouldered member on the next movement of the feeler forwardly to effect a change in the loom operation, and means effective on forward movement of the shouldered member to withdraw the feeler forwardly.
10. In a feeler mechanism for looms, the combination of a magnetic feeler adapted to be drawn rearwardly on detection of substantial exhaustion of filling, a stop for limiting the rearward movement of the feeler as the lay goes back, a dog adapted to be positioned for movement by the lay, a dog positioner member, a shouldered member adapted to act upon the positioning member, bearings in which the feeler is movable towards the shouldered member for engagement therewith when the feeler is drawn rearwardly, and means to move the shouldered member on the next movement

of the feeler forwardly to effect a change in the loom operation.

11. In a feeler mechanism for looms, the combination of a magnetic feeler adapted to be drawn rearwardly as the lay goes back, chamfered bearings in which the feeler may move transversely to its rearward movement as the feeler is drawn rearwardly, a shouldered member adapted to be engaged by the feeler when it is drawn rearwardly, a dog, a dog positioner adapted to be actuated by the shouldered member when it is moved forwardly by the feeler, and a bunter on the lay for engaging the dog to effect replenishment of filling.

12. In a feeler mechanism for looms, the combination of a magnetic feeler that is drawn rearwardly on detection of substantial exhaustion of the filling, a shouldered member that is operatively engaged by the feeler when it is drawn rearwardly, a dog, a dog positioner which is initially moved by the shouldered member, a part on the lay for insuring full movement of the dog positioner member, and a bunter on the lay for engaging the dog.

In testimony whereof, I have signed my name to this specification.

JOHN C. BROOKS.
